DIVING BELL

Hugh D. Wilson, Goleta, Calif., assignor to Union Carbide Corporation, a corporation of New York

Filed Feb. 13, 1964, Ser. No. 78,616

Term of patent 3½ years

(Cl. D71—1)

Fig. 2

Fig. 1

Fig. 3

FIG. 1 is an elevational view of a diving bell showing my new design;

FIG. 2 is a top plan view; and

FIG. 3 is a bottom plan view.

The side not shown is identical to FIG. 1.

I claim:

The ornamental design for a diving bell, as shown and described.
